UNITED STATES PATENT OFFICE.

PHILIP NATHANSON, OF ALLENTOWN, PENNSYLVANIA.

STOP MOTION FOR BOBBIN WINDERS.

Application filed April 15, 1922. Serial No. 552,892.

To all whom it may concern:

Be it known that I, PHILIP NATHANSON, a citizen of the United States, and a resident of Allentown, county of Lehigh, and State 5 of Pennsylvania, have invented a new and useful Stop Motion for Bobbin Winders, of which the following is a specification.

While applicable to bobbin winding mechanism generally, my invention is designed more particularly for use in conjunction with means for transferring silk, cotton, or other yarn or thread, from a skein on a "swift" or reel to a bobbin on a winding spindle, as for instance in connection 15 with the usual "winding frames" known in the art.

The object of my invention is to attain an automatic bobbin wind-stop device of the character designated of simple, inexpensive, 20 but substantial and unobtrusive construction, automatic and "fool proof" in operation, whereby yarn waste is practically eliminated, and time and labor saved, the invention consisting essentially in the specific combination 25 and arrangement of parts and appurtenances described and claimed, and a distinctive feature being the provision of brake means actuated directly by the yarn mass as deposited on the bobbin in such manner that 30 a "full" bobbin releases itself from further rotation, all as hereinafter fully set forth.

In the accompanying drawings,

Fig. 1, is a more or less diagrammatic representation of a vertical section of a winding frame such as is well known in the art, showing the application thereto of one of my automatic yarn wind stop attachments;

Fig. 2, is an elevation of a bobbin spindle, with a bobbin thereon shown in section;

Fig. 3, is a top view of one of my automatic yarn mass bobbin stop attachments as positioned in Fig. 1;

Fig. 4, is a perspective view of one of my automatic yarn mass stop attachments illustrating its co-relation to the winding frame and operative parts thereof;

Fig. 5, is a perspective view of a bracket on which the operative parts of my automatic yarn mass stop device are mounted;

Fig. 6, is a detail view of the rock lever on which the winding feeler is mounted;

Fig. 7, is a diagrammatic view illustrating the operation of my automatic yarn mass bobbin stop attachment.

I herein show and describe a practical embodiment of my invention as in the form

of an attachment to winding frame and actuating mechanisms well known in the art, although the essential parts of my device and features of my invention may obviously be 60 permanently incorporated in yarn winding apparatus of this class with like results and benefit. The fact however that my automatic stop device may be added to existing yarn winding machinery without alteration of the latter, and simply as an adjunctive appliance, is an important practical advantage from a commercial point of view, and in this respect my device is unique and self-contained in that a single clamping screw or 65 equivalent mechanical expedient is all that is necessary to position the same in operative relationship to the bobbin spindle mounts at present in vogue in the art in machines of 70 the character designated.

For this reason, in the accompanying drawings I show and indicate only sufficient of the winding frame parts and mechanism to illustrate the co-relation of my automatic stop device thereto. Thus R, Fig. 1, represents the usual skein "swift" or reel from which the silk or other yarn is to be transferred to the bobbin B, and A, A, the ordinary longitudinal rear members of the frame of the apparatus to which the usual bobbin spindle supporting brackets α , α , are attached, said longitudinal members A, A, ordinarily consisting of parallel tubing. D, represents the usual continuously rotatable drive shaft on which the steel drive pulleys d , are rigidly mounted. The spindle supporting brackets α , α , are formed with the customary notches or recesses α' , α' , for the reception of the ends of the spindles S, on which the bobbins B, are detachably 90 mounted as heretofore, said spindles S, being each provided with a preferably non-metallic head or pulley s , (hereinafter designated as the spindle head) for contactual engagement with the upper peripheral surface of a metallic drive pulley d , and the construction, arrangement and operation of the parts thus far disclosed being essentially the same as heretofore in 95 yarn winding mechanism of this class.

The operative parts of my automatic stop attachment are mounted on an L-shaped bracket L, secured to the aforesaid longitudinal members A, A, of the frame of the apparatus by means of a clamping nut C, 100 engaging with a screw c , the head c' , of which bears against the face of said bracket 110

L, and the shank of which extends through a vertical slot l, in the upright member of said bracket L, and extends between said longitudinal members A, A, of the frame 5 and engages with the female screw thread formed for the purpose in the aforesaid clamping nut C, as indicated more particularly in Fig. 1, of the drawings. The slot l, in the vertical member of the bracket L, 10 provides for the adjustment of my automatic yarn stop attachment as a unitary device in accordance with the diameter of the bobbin B, to be used in connection therewith, or of the desired fullness of yarn mass thereon.

15 The forward end of the horizontal member of the supporting bracket L, is bifurcated to accommodate the forward end of the rock lever E, which is fulcrumed thereon. On the forward end of this rock lever 20 E, is mounted a transverse feeler F, for contacting with the under side of the yarn mass on the bobbin B. This feeler F, is of a length slightly less than the distance between the end flanges on the bobbin B, 25 so as to be capable of entrance therebetween; and its contactual surface preferably consists of the periphery of a roller pivotally supported between the upturned ends of a wire stirrup e, or otherwise mounted on the rock lever E, in such manner as to be rotatable on its longitudinal axis, so as to reduce frictional contact with the yarn to a minimum degree while holding the feed thereof taut and even.

30 To the rear end of the rock lever E, is pivotally attached a coupling rod h, the upper end of which is in turn pivotally connected with the crank arm k', of a rocker member k, fulcrum mounted on the upper portion of the bracket L. The free end of the crank arm k', of the rocker member k, is formed with a pendent extension h², to the lower portion of which the rear end of the brake plate p, is pivotally connected.

35 The rocker member k, is preferably although not necessarily made of wire, in which case the fulcrum end thereof may be extended beyond the bracket L, and bent over to constitute a stop k³, which, by contacting with the face of said bracket L, will limit the extent of motion or play of the said rockable member in either direction. The operative parts of my device are so proportioned and arranged that the free end 40 of the brake plate p, rests continuously upon the rear upper peripheral surface of the drive disc or pulley d. The weight of the rear portion of the rock lever E, the coupling or connection rod h, and the crank arm k', and pendent h², are such as to tend constantly to retract the free end of the brake plate p, out of contact with the pulley head s, of the spindle S,—the stop k³, however preventing the collapse of the parts 45 and the withdrawal of said free end of the

brake plate p, from the periphery of the drive pulley d, and maintaining the said parts in what may be designated for convenience as their normal position, with the feeler F, protuberant between the flanges of 70 the bobbin B, presuming the latter to be a fresh bobbin to be filled.

Under these conditions, as the bobbin fills up with the feed of yarn from the reel R, the increase of wind will gradually act 75 upon the feeler F, to depress the outer end of the rock lever E, thereby raising the rear end thereof and causing the connection rod h, to raise the crank arm k, and thereby advance the free end of the brake 80 plate p, until it protrudes between the periphery of the drive disc d, and the spindle head s, in such manner that when the requisite amount of yarn on the bobbin is effected the brake plate p, will force the said spindle head s, out of direct contact with said drive wheel d, and thereby prevent the further rotation of the spindle S. Thus the winding of yarn is stopped automatically, the yarn mass itself being utilized for the purpose. 85

Upon the removal of the filled bobbin and its spindle the operative parts of my device automatically, by gravity, return to normal positions and relationship, to resume the functions described upon replacement of 90 spindle and bobbin, and so on continuously without interference with the operation of the winding frame mechanism in any particular.

By this means I insure uniformity in 100 length of winding on the bobbins, and eliminate the uncertainty incidental to the old method of reliance on the judgment or guess work of the attendant or "winder", so called, who has simultaneously to watch and care for a hundred or more bobbins. In other words, the operator is relieved of all responsibility for the length or condition of winding on the bobbin, and the fear of 105 excess of winding is obviated, so that skilled labor may be dispensed with, since the attendant has simply to remove and replace stationary spindles and bobbins at convenience. 110

It will be seen that my automatic bobbin 115 winder stop device is very simple and inexpensive of structure, gears, springs and complication of parts being avoided, and gravity alone being utilized as the actuating power. Furthermore it does not encroach 120 on the winding frame mechanism to which it is attached, or with which it may be incorporated, its action being essentially local in the sense that it concerns only the spindle and bobbin positioned in front of it, and does not impede the insertion or removal thereof, in the usual manner. No resetting 125 of the device is required, it being independent and self-contained in this respect; requiring no attention whatsoever from the 130

attendant; and it is entirely out of the way and not subject to contact with extraneous objects.

What I claim as my invention and desire 5 to secure by Letters Patent is,

1. In combination with bobbin spindle drive mechanism of the character designated, an automatic stop device comprising a rock lever, a rotatable yarn mass feeler 10 mounted on said rock lever, and a brake plate connected therewith by intermediate means and adapted to be protruded thereby between the spindle drive wheel and the spindle head by means of the accumulation 15 of yarn mass on the bobbin, substantially in the manner and for the purpose described.
2. In combination with bobbin spindle drive mechanism of the character designated, an automatic stop device, comprising a rock 20 lever, a rotatable yarn mass feeler mounted on said rock lever, a coupling rod pivotally connecting said rock lever with a rockable crank arm, said rockable crank arm, and a brake plate pivotally connected therewith 25 and adapted to be protruded thereby between the spindle drive wheel and the spindle head by means of the accumulation of yarn mass on the bobbin, substantially in the manner and for the purpose described.
3. In combination with bobbin spindle 30

drive mechanism of the character designated, an automatic stop device comprising a rock lever, a rotatable yarn mass feeler consisting of a roller rotatably mounted on said rock lever, and a brake plate connected 35 therewith by intermediate means and adapted to be protruded thereby between the spindle drive wheel and the spindle head by means of the yarn mass on the bobbin, substantially in the manner and for the purpose 40 described.

4. In combination with bobbin spindle drive mechanism of the character designated, an automatic-stop device comprising a bracket adjustably mounted on the winding frame, a rock lever mounted on said bracket, a rotatable yarn mass feeler mounted on said rock lever, a rockable crank arm, a coupling rod pivotally connecting said rock lever with said rockable crank arm, 45 and a brake plate pivotally connected therewith and adapted to be protruded thereby between the spindle drive wheel and the spindle head by means of the accumulation of yarn mass on the bobbin, substantially in 50 the manner and for the purpose described.

PHILIP NATHANSON.
